Corporation, San Francisco, Calif., a corpora-
tion of Nevada

Application July 5, 1950, Serial No. 172,132

3 Claims. (Cl. 143—157)

1

This invention relates to the sawing of slabs from the sides of logs and an object of the invention is to provide mechanical off-bearing means by which the slab, as it is being sawed from the log, will first be partly supported to reduce the tendency to split off from the log before the sawing is completed, and then, when it is entirely separated from the log, can be controlled and directed and moved rapidly and easily into a desired position with the flat side down.

A further object of the invention is to provide additional and supplemental off-bearing means to be used in conjunction with slab-positioning rolls, and, specifically, with the particular type of positioning rolls described in U. S. Patent No. 2,468,036, issued April 26, 1949.

The construction and mode of operation of our improved mechanical off-bearing means will be readily understood from the following brief description. In the description reference is made to the accompanying drawings in which:

Fig. 1 is an elevation of the device comprising the off-bearing means and showing also the forward end of the log carriage with a log mounted thereon and a slab in the act of being cut from the log, a portion of the mechanism for the off-bearing means being broken away and shown partly in section for the sake of clarity; and

Fig. 2 is a corresponding plan view.

The log L from which the slab S is being cut by means of the usual band saw (portion of the band saw being indicated by 10 in Fig. 1), is supported on a moving carriage 11 of well-known type, and the log is held in position by the customary adjustable knees 12 and dogs (not shown), as the carriage moves the log longitudinally in the direction indicated by the arrow x in Fig. 2.

A plurality of slab-positioning rolls 13, having conically-shaped and enlarged ends adjacent the side of the carriage, are driven in unison from a shaft 14 with which they are connected by suitable pairs of gears 15 and 16. Such slab-positioning rolls are described in detail in U. S. Letters Patent No. 2,468,036, previously mentioned and need not here be further described.

When the slab S is being cut from the log L there is a tendency as the saw approaches the end of the log for the slab to split off due to the weight of the portion of the slab which has been sawed. One of the purposes of our device is to provide some support for the slab at this period to reduce the tendency to split off from the log. When the slab is entirely separated from the log it drops onto the rolls 13 at first in some such position as that indicated by the broken line po-

sition S' in Fig. 1. The purpose of our mechanical off-bearing means then is to facilitate the sliding of the slab into the desired final position on the rolls 13, that is with the sawed face of the slab down.

A swinging frame, including a horizontal platform 17 which is rigidly attached at one end to a vertical member 18, is hinged to an upright post 19 by suitable hinges 20, as shown in Fig. 1, so as to swing in a horizontal plane. A pair of parallel vertical uprights 21 are rigidly mounted on the free end of the platform 17, and tie rods 22 connect the upper ends of these uprights 21 with the top of the member 18, thus forming a more rigid structure. This structure or swinging frame is also reinforced by a pair of triangular-shaped braces 23 extending from the platform 17 to the upright member 18. A pair of wheels 24, carried in suitable mountings attached to the underside of platform 17, act as an additional support for the free end of the swinging frame. These wheels 24 are arranged so as to roll on a curved horizontal track 25 which in turn rests on a stationary base block 26.

While the swinging frame is free to swing in one direction its swing in the opposite direction is limited by a stop block 27. A rope or cable 28, attached to the swinging frame passes over a pulley 29 and a weight W is attached to the other end of the cable 28 and acts to bring the swinging frame back into position against the stop block 27. Suitable cushioning means (not shown), may be provided on the stop 27, or on the adjacent side of the swinging frame, if desired, to cushion the jar when the swinging frame is brought back into position against the stop 27 by the action of the weight W and cable 28.

A vertical pivoting bracket 30 is pivotally supported near the top between the pair of uprights 21. The top of this vertical pivoting bracket 30 is formed into a tubular housing 31 in which the end of a rod 32 is slidably mounted. A pin 33 extends diametrically through the tubular housing 31 and through a longitudinal slot 34 provided in the rod 32, and thus limits the extent of the telescoping or sliding movement of the rod 32 in the housing 31. A coil spring 35 is located between the inner end of the rod 32 and an adjustable disk 36 located in the corresponding end 50 of the housing 31. This spring tends to keep the rod 32 in its maximum extended position. An adjusting screw 37, connected with the disk 36, and extending through a cap attached to the end 55 of the housing 31 enables the tension of the spring 35 to be adjusted slightly when desired.

A pair of small parallel vertical plates 38, attached to opposite sides of the end of the rod 32, provide a mounting for a stub shaft 39. The inner end of stub shaft 39 is pivotally supported on a bolt 40 extending through the plates 38. A pin 41 extending through holes provided in the plates 38 and through a hole in the stub shaft 39 holds the stub shaft 39 in a desired predetermined position. A row of holes in the two plates 38, through which the pin may extend, enable the position of the stub shaft 39 to be adjusted, as apparent from Fig. 1.

A rotatable head 42, preferably shaped as shown in Figs. 1 and 2, is mounted on the stub shaft 39, suitable means being provided to hold the head on the stub shaft while allowing the head to rotate freely. The outside surface of the head 42 may be covered with small spikes (not shown), or may be roughened or covered with any surfacing which will cause the head to engage the bark surface of the slab S when the head 42 is brought into contact with the slab in the position indicated in Figs. 1 and 2. Thus the pivoting bracket 39, rod 32, and stub shaft 39 constitute in effect a composite adjustable arm, carrying an engaging element, for contacting and engaging the slab which is being sawed from the log.

A rack bar 43 is pivotally connected to the bottom of the pivoting bracket 30. The rack bar is slidably supported for horizontal sliding motion and is engaged by a pinion 44 which is driven, through the intermediary of suitable gearing, by a reversible motor 45.

The operation of the device briefly is as follows: The operator stands near the controls (not shown) of the reversible motor 45. Before starting the operation the bar 32, and with it the head 42, is raised slightly above the level of the top of the log L. The platform 17 of the swinging frame will be in the starting position shown in Fig. 2, that is, will be resting against the stop 27, having been brought to that position by the pull of the cable 28 with the attached weight. The operator lowers the bar 32 until the head 42 contacts the slab which is being sawed. Since the slab is moving at fairly rapid speed there will momentarily be a tendency for the end of the bar to swing in the same direction in spite of the fact that the head is rotatably mounted. The swing frame will permit such side swing to take place and thus takes up the shock which would otherwise be delivered to the arm at the first impact of the head with the slab. The lowering of the bar 32 is done, as previously explained, by the operation of the motor 45 and the moving of the rack bar 43 to the right as viewed in Fig. 1. The operator momentarily stops further operation of the motor and watches the slab. The engagement of the head 42 with the surface of the slab, due to the shape of the head and the engaging elements on the surface of the head, will help to hold up the forward portion of the slab while the saw is completing the cut. When the sawing of the slab is approximately completed the motor is again operated to lower the bar 32 to enable the head 42 to follow the slab as it drops downwardly. Continued operation of the motor in the same direction causes the head 42 not only to continue in contact with the slab, but, when the slab is in some such position as indicated by the dotted lines in Fig. 1, to push downwardly on the slab so as to bring it down quickly into the desired final position on the rolls 13 with the sawed flat face on the bottom of the slab resting on the rolls. As soon as the slab is in the

final desired position, the motor 45 is reversed by the operator. This lifts the head 42 from the slab and raises the rod 32 and head 42 in readiness for being brought down into contact with the slab to be cut from the next log.

We claim:

1. In a mechanical off-bearer assembly for facilitating the handling of a slab as it is being cut from a log, a frame located a spaced distance from the log and on the slab side of the log, said frame mounted for limited swing in a horizontal plane, an arm mounted on said frame and extending towards said log and slab from said frame, means for moving said arm up and down, a member 10 rotatably mounted on the end of said arm and so positioned as to be contacted by and to bear against the slab when said arm is in starting position, said member rotated substantially in the direction of the log travel by contact with the slab, 15 and slab-conveying means located below the slab and said member for receiving the slab when the severing of the slab from the log is completed, whereby said member when first contacted by the slab, by exerting an outer side thrust against the slab, will prevent the slab momentarily from tipping outwardly from the log, and whereby said member and said arm can be moved downwardly with the slab when the slab is severed from the log to facilitate the sliding of the slab into desired position on said slab-conveying means.

2. In a mechanical off-bearer assembly of the character described, a frame located a spaced distance from the log and on the slab side of the log, said frame mounted for limited swing in a horizontal plane, an arm mounted on said frame and extending towards said log and slab from said frame, means on said frame for moving said arm up and down in a vertical plane, the plane of said up and down movement of said arm being perpendicular to the axis of the log when said frame is in normal position, a member rotatably mounted on the end of said arm and so positioned as to be contacted by and to bear against the slab when said arm is in starting position, said member rotated substantially in the direction of the log travel by contact with the slab, said member having a surfacing for frictionally engaging the outer surface of the slab, and slab-positioning rolls located below the slab and said member for receiving the slab when the severing of the slab from the log is completed, whereby said member when first contacted by the slab, by exerting an outer side thrust against the slab, will prevent the slab momentarily from tipping outwardly from the log, and whereby said member and said arm can be moved downwardly with the slab when the slab is severed from the log to facilitate the sliding of the slab into desired position on said rolls.

3. A mechanical off-bearer assembly of the character described for facilitating the handling of a slab as it is being cut from a log, said assembly including a frame located a spaced distance from the log and on the slab side of the log, said frame mounted for limited swing in a horizontal plane, a composite arm mounted on said frame and extending towards said log and slab from said frame, means on said frame for moving said arm up and down in a vertical plane, the plane of said up and down movement of said arm being perpendicular to the axis of the log when said frame is in normal starting position, means for bringing said frame to said normal starting position, a head rotatably and adjustably mounted

on the end of said arm and so positioned as to be contacted by and to bear against the slab when said arm and said frame are in starting position, said head rotated substantially in the direction of the log travel by contact with the slab, said head having engaging elements on its surface for engaging the outer surface of the slab, and off-bearing rolls located below the slab and said head for receiving the slab when the severing of the slab from the log is completed, whereby said head when first contacted by the slab, by exerting an outer side thrust against the slab, will prevent the slab momentarily from tipping outwardly from the log, and whereby said head and said arm can be moved downwardly with the slab when the slab is severed from the log to facilitate the sliding of the slab into desired position on said rolls.
